PNEUMATIC POSITIONING WORK SUPPORT

Walter F. Kuhlman, Norwalk, Ohio, assignor to Kuhlman Machine Company, Norwalk, Ohio, a corporation of Ohio

Filed Mar. 11, 1968, Ser. No. 10,911

Term of patent 14 years

U.S. Cl. D54—13

FIG. 1 is a perspective view showing a pneumatic positioning work support embodying my new design;

FIG. 2 is a plan view of the pneumatic positioning work support shown in FIG. 1;

FIG. 3 is a side view of the pneumatic positioning work support shown in FIG. 1;

FIG. 4 is an end view of the left end of the pneumatic positioning work support shown in FIG. 1; and

FIG. 5 is an end view of the right end of the pneumatic positioning work support shown in FIG. 1.

I claim:

The ornamental design for a pneumatic positioning work support, as shown.
